UNITED STATES PATENT OFFICE.

WILLIAM H. DAVIS, OF BRONXVILLE, AND FREDRICK E. JOSS, OF BROOKLYN, NEW YORK, ASSIGNEES TO LEKTOPHONE CORPORATION, A CORPORATION OF DELAWARE.

PHONOGRAPH TRANSMISSION-ROD.

1,312,957.

Specification of Letters Patent. Patented Aug. 12, 1919.

Application filed May 9, 1918. Serial No. 233,465.

To all whom it may concern:

Be it known that we, WILLIAM H. DAVIS and FREDRICK E. Joss, both citizens of the United States, residing at, respectively, 5 Bronxville, county of Westchester, State of New York, and borough of Brooklyn, county of Kings, city and State of New York, have invented certain new and useful Improvements in Phonograph Transmission-Rods; 10 and we do hereby declare the following to be a full, clear, and exact description of the invention, such as will enable others skilled in the art to which it appertains to make and use the same.

15 This invention relates to sound-reproduction, and it proposes, briefly, an improved vibration transmission device for connection to the diaphragm of a sound-reproducing mechanism, such device being designed primarily for use in a machine or apparatus of the general type shown and described in 20 U. S. Letters Patent to Marcus C. Hopkins, No. 1,271,527 of July 2, 1918.

In machines of the character indicated, 25 there is employed a large conical diaphragm of some strong and yet light vibratile material, which is freely exposed to unconfined air and has imparted to it, by means of a transmission connection, the vibrations imposed upon or against a record or equivalent element. The arrangement in these machines is such that the diaphragm is subjected, 30 along a line coincident with its axis, to the action of the aforesaid vibrations, and is thereby enabled to produce self-sustaining sound-waves substantially corresponding in 35 intensity with the original sound-waves, so that the diaphragm thus takes the place not only of the usual sound-box, but also of its accompanying horn or like amplifier.

It has been found, however, that some slight sound-distortion occurs in sound-reproducing instruments constructed in accordance with the precise disclosure in the 45 above-identified application. This may possibly be explained on the theory that the rod-like transmission device employed interferes in some way, due to the resonant nature of the material of which it is constructed, with the passage of the sound-vibrations 50 from phonic line to diaphragm by way of such device; that is to say, the transmission rod, if constructed entirely of metal, will inherently set up or emit a distinct tonal vi- bration which is additional to, and not in strict accord with, the particular sound to be transmitted, during the passage of the stylus along the phonic line of a record. Such abnormal vibration of the rod must, obviously, by accentuating the fundamental note of the rod itself, disturb the wave form of the sound then being sought to be regenerated and distort the quality thereof upon regeneration. The essential object of the present invention is, therefore, to overcome this distortion, produced, as just explained, by the interference of the natural vibrations of the transmission rod with the passage of the sound-vibrations through said rod to the diaphragm; such object being accomplished by the provision of a single transmission rod comprising at least two longitudinal sections or members arranged in endwise alignment and constructed of material of dissimilar resonance, one of such sections serving to neutralize or block the independent sound vibration emitted by the other section. The attainment in this way of the object specified, that is, by the employment of a rod of the character described, or, in any event, the attainment of extremely advantageous results in sound-reproduction along these lines by the use of such rod, as compared with the transmission connection utilized in the earlier construction, is advanced in consequence of a series of experiments, conducted with the utmost care and extending over a considerable period of time. The precise theory which controls the situation, and which is really responsible for the improvements in question, may actually involve conditions and factors in addition to those stated above, and which possibly even differ somewhat from them, and the above theory is presented merely as a tentative explanation of the results obtained by or from the invention.

The accompanying drawing shows one form which the invention may take when applied to, or installed in, a Hopkins-type sound-reproducing machine; but it is to be understood that no limitation to the precise structural details therein disclosed is contemplated, excepting in so far as may be determined by the scope of the invention as subsequently claimed. Also, the invention is not to be regarded as limited to the use of its component parts or features in the

particular combinations illustrated in said drawing, since such parts are susceptible of use independently of one another in other and different environments.

5 In the drawing:

Figure 1 is a vertical sectional view taken axially through the reproducing mechanism of a Hopkins-type machine equipped with the invention;

10 Fig. 2 is an enlarged detail view of a transmission rod of the form shown in Fig. 1. Fig. 3 shows a slightly modified form of rod; and

15 Fig. 4 is a broken longitudinal section, on a further enlarged scale, showing certain of the parts illustrated in Fig. 1.

Referring to Fig. 1, the invention, which, as originally stated, comprises a rod-like transmission member 5, is represented as 20 applied to, or associated with, a Hopkins-type diaphragm 6, between which latter and the stylus holder 7 it is interposed. The diaphragm 6 is of the general character disclosed in the Hopkins patent, above 25 identified, to which reference may be had for a complete description of its theory of operation and preferred dimensions. For all present purposes, it is sufficient to state that the diaphragm comprises a conical portion 30 of light, vibratile material which, when vibrated from a record or equivalent sound-vibrated element, is thereby enabled to produce self-sustaining sound-waves of substantially the same intensity as the original 35 sound-waves, so that it replaces both the old sound-box and the usual accompanying horn, as has previously been explained. The diaphragm is rigidly supported at its periphery between a pair of clamping rings 40 8 and 9, which are fastened together by screws, or in some other suitable manner, and are carried by a spider 10, the hub of the latter being mounted upon one end of a tubular supporting bar 11. The bore 12 of 45 this bar extends therethrough from end to end and provides a passage within which the transmission rod or interponent is received. The opposite ends of the rod project beyond the bar 11, the rear end of said 50 rod being equipped with a conical cap 13, which engages the apex of the conical portion of the diaphragm. The front end of the bar has fitted on it a cylindrical cap or sleeve 14, within which are accommodated the projecting front end of the transmission rod and a portion of the stylus holder 7, the aforesaid rod end being here shown as connected to the stylus holder by means of a screw 15 which passes through a 55 lateral extension on the holder and into the rod. The end of the holder in which the stylus is actually received projects outwardly through an aperture in the cap 14, as will be understood. The holder is preferably connected to the adjacent end of the

supporting bar 11 by a resilient member 17, secured at opposite ends to said holder and bar end, and acting as a spring mounting for the former which enables it to vibrate with marked freedom and which avoids 70 pivot-chatter and other disturbing noises of like nature. The diaphragm cap 13 may advantageously consist of inner and outer conical plates of comparatively stiff material, which clamp the apex of the diaphragm 75 tightly between them, the hub portions of said plates being threaded together, as shown in Fig. 4, to couple the plates together. The inner of the two plates has its hub extended or elongated and provided with internal 80 threads thus forming a cylindrical socket for the reception of a centrally-apertured plug 18, through which is inserted a screw 19 which projects at its inner end into a threaded aperture in the adjacent end of the 85 transmission rod 5.

The transmission rod, as stated above, constitutes the subject of the present invention, and comprises a plurality of separately-constructed sections or members connected 90 together in endwise or axial alignment and formed of materials possessing different degrees of resonance. In the construction illustrated, the rod embodies two main sections 20 and 21, made respectively, of non-metallic and metallic materials, preferably 95 wood and steel, the latter in the form of a strip of wire and, in addition to these two main sections, two short or auxiliary sections 22 and 23, which are, or may be, made of 100 brass, the section 22 coupling together the adjacent ends of the aforesaid main sections, while the section 23 couples the front end of the wooden main section 20 with the stylus holder and is apertured to receive the 105 end of the screw 15. The ends of the wooden section are provided with reduced, externally-threaded extensions 24, and the front end of the steel section 21 has a similar extension 25, these extensions 24 and 25 engaging in internally-threaded, axial sockets 26 and 27 in the coupling sections 23 and 22. 110

The two main sections 20 and 21 may have different lengths, as is the case with the rod 5, represented in Figs. 1 and 2, in which the 115 wooden section is approximately three times as long as the steel section; or they may have substantially the same length, as in the rod illustrated in Fig. 3, the method of building up the rod being the same in both instances. Still other relative proportions may be adopted if desired. The non-metallic front section 20 preferably has a greater thickness than the metallic rear section 21, this holding good for both forms of the rod 120 as shown and described.

We claim:

1. A long, thin phonograph transmission rod adapted to be connected at opposite ends with a stylus holder and a diaphragm and 130

to be vibrated by the travel of the stylus along a sound groove, comprising a section inherently adapted to set up independent tonal vibrations during the travel of the stylus, and a section of differently-resonant material for neutralizing such independent vibrations, said sections alining and abutting end to end.

5 2. A long, thin phonograph transmission rod adapted to be connected at opposite ends with a stylus holder and a diaphragm and to be vibrated by the travel of the stylus along a sound groove, comprising a metallic section inherently adapted to set up independent tonal vibrations during the travel of the stylus, and a non-metallic section for neutralizing such independent vibrations, said sections alining and abutting end to end.

10 3. A long, thin phonograph transmission rod adapted to be connected at opposite ends with a stylus holder and a diaphragm and to be vibrated by the travel of the stylus along a sound groove, comprising a metallic section inherently adapted to set up independent tonal vibrations during the travel

of the stylus, and a wooden section for neutralizing such independent vibrations, said sections alining and abutting end to end.

15 4. A phonograph transmission element adapted to be connected at opposite ends with a stylus holder and a diaphragm and to be vibrated during the travel of the stylus along a sound groove, said element comprising a metallic section adapted to emit a definite, audible sound-vibration independently 30 of the vibrations imparted to it by the stylus during the travel thereof, and a long, thin wooden section for neutralizing such independent vibration, said sections alining and abutting end to end.

20 5. A long, thin phonograph transmission element adapted to be connected at opposite ends with a stylus holder and a diaphragm and to be vibrated by the travel of the stylus along a sound groove, comprising two sections of differently resonant materials alining 35 with each other and abutting end to end.
